United States Patent Office

Des. 188,816
Patented Sept. 13, 1960

188,816

FLEXIBLE DISPENSING BOTTLE

Arthur A. Friedberg, 451 Walton St.,
West Hempstead, N.Y.

Filed Sept. 17, 1959, Ser. No. 57,583

Term of patent 14 years

(Cl. D58—8)

FIG. 2

Figure 1 is a front elevational view of a flexible dispensing bottle, showing my new design. The side not shown is the same as the side shown.

I claim:

The ornamental design for a flexible dispensing bottle, as shown and described.
